UNITED STATES PATENT OFFICE.

WILLIAM A. DOBSON, OF WINDSOR, CONNECTICUT, ASSIGNOR TO UNDERWOOD TYPE-WRITING COMPANY, OF NEW YORK, N. Y., A CORPORATION OF DELAWARE.

TYPE-WRITING MACHINE.

1,247,240.

Specification of Letters Patent. Patented Nov. 20, 1917.

Application filed June 3, 1916. Serial No. 101,454.

To all whom it may concern:

Be it known that I, WILLIAM A. DOBSON, a citizen of the United States, residing in Windsor, in the county of Hartford and State of Connecticut, have invented certain new and useful Improvements in Type-Writing Machines, of which the following is a specification.

This invention relates to means for holding work upon the platen of a typewriting machine, particularly a revoluble platen, certain features of the invention especially adapting it also for use with a platen that is shiftable to different case positions.

An object of the invention is to provide a serviceable work-holding device which is small, compact, inexpensive and reliable and readily adapted to existing machines, more particularly those of the Underwood type, for holding cards or other small work-pieces and enabling them to be typewritten close to the top and bottom edges, as well as their side edges.

In the patent to Lasar, 415,533, is disclosed a work-holding means comprising rolls mounted upon the machine frame and running upon the visible side of the platen, to roll thereon as the carriage moves in letter-feeding direction. These rolls may be arranged one on each side of the printing point. Said Lasar rolls are arranged with their axes perpendicular to the platen axis, so that they may roll on the platen or work-piece thereon as the carriage travels, and are spring-pressed against the platen, so as to be capable of holding the work-piece permanently against the platen near the printing point, the work-piece being thus kept in position for being printed upon.

According to one feature of my invention, the rolls proper may be provided with barrels which are elongated to extend downwardly a considerable distance below the printing line, and the downwardly-extending portion of each roll may serve as a deflector or guide by which the leading edge of the work-piece, as it is advanced beyond the usual platen feed rolls at the lower front side of the platen, is guided to the printing line, where it is finally pressed between the rolls and the platen. The rolls may be mounted to rotate on spindles provided by

arms, which, at their lower ends, are pivoted on brackets on the usual type-bar segment. Pressure of the rolls against the platen may be effected by flat springs held in effective position by restraining arms, which may be shiftable out of operative position, to remove the pressure of the rolls against the platen.

The rolls may be located between the wing scales, which are usually mounted upon the type-bar segment to bear at their upper edges against the front of the platen along the base of the printing line when the platen is in lower case position. The work-holding ends of the rolls extend above the upper edges of these scales and hold the work-piece when the bottom edge thereof is close to the printing line and has been carried upwardly beyond said scales, either by the line-space rotation of the platen or by shifting the platen to upper-case position. If the platen is now returned to such position that the bottom edge of the work-piece is carried below the printing line, said edge will come down in front of the scales, but that portion of the card between the rolls will still be held firmly against the platen, so that the card can always be written upon, even if the outlying side portions thereof stand in front of the scale. Then as the carriage is moved from right to left, or vice versa, the side edge of the card will slip off the inner edge of the underlying wing scale, so that upon the next movement of the carriage in the opposite direction, said edge will slip under the scale.

Each of the work-holding rolls may be mounted to slide up and down on its supporting arm. This feature is especially useful at the case-shifting operation, when the platen rises bodily to bring a different set of types into use. To facilitate this sliding, each roll may run upon a double row of bearing balls, which also facilitate the rotation of the rolls. The efficiency of the device is thereby enhanced, because it is practical to obtain an effective pressure of the rolls against the card without offering any appreciable amount of resistance to the movement of the card in case-shifting direction. There is thus secured a firm pressure of the card against the platen at all times.

adjacent the printing point without offering more than a negligible resistance to the upward movement of the card.

Other features and advantages will hereinafter appear.

In the accompanying drawings,

Figure 1 is a front perspective view of a portion of an Underwood typewriting machine, with the present invention applied thereto.

Fig. 2 is an elevation showing the work-holding rolls and their relation to the platen when the latter is in upper-case position.

Fig. 3 is a view showing a work-holding roll, a scale-plate and associated parts, disconnected.

Fig. 4 is a sectional elevation of the machine, various parts being omitted.

Fig. 5 is a section at the line 5-5 on Fig. 2.

Fig. 6 is a view similar to Fig. 5, but with the work-holding roll and platen in lower-case position.

The revoluble platen 10 is rotatably mounted in a platen frame 11, shiftable to upper and lower-case positions on the carriage 12, which runs on front and rear guide-rails 13 and 14. Type-bars 15 are pivoted on a fulcrum 16 on a stationary type-bar segment 17, to swing upwardly and rearwardly to the front face of the platen, to cause the upper and lower-case types 18 and 19 to print at the platen along the printing line *a-b*; Fig. 2. The type-bars are actuated by keys 20 on key-levers 21 fulcrumed at 22 and connected through bell-cranks 23 to the type-bars. The platen is shiftable to upper-case position by means of shift keys 24 and 25, fulcrumed on the rod 22 and having upstanding arms 26 to actuate the platen-shifting frame 27, comprising a rock-shaft 28. The shift frame 27 also comprises a shift-rail 29, on which runs a roll 30 on the platen frame. When a shift key is depressed, the connected arm 26 thereof swings the shift-frame 27 about 28 as an axis, thereby causing the rail 29 to lift the platen into position for the upper-case types 18 to print thereon.

The carriage may be driven in letter-feed direction by the usual spring drum (not shown), the letter-feed movements being controlled by escapement mechanism, comprising an escapement wheel 31 driven by an escapement pinion 32 which runs on a rack 33 on the carriage. The rotation of the escapement wheel is controlled by escapement dogs 34 on a dog rocker, pivoted at 35 and actuated by a universal bar 36, which is moved rearwardly at each type stroke by a heel 37 on the actuated type-bar.

The platen may be rotated to line-space the work by means of line-spacing mechanism (Fig. 1), comprising a line-spacing lever 38 operable to move rearwardly a slide bar

39, on which is mounted a pawl 40, to drive a line-space ratchet wheel 41 on the platen axle, and thereby rotate the platen. The platen may also be rotated in either direction by the usual hand-wheels 42, secured to the ends of the platen axle. Work-sheets may be introduced to the machine by placing them on the paper-shelf 43 behind the platen and then rotating the latter to advance the sheets around the underside of the platen between the same and the rear and front feed-rolls 44 and 45, respectively, and upwardly past the printing line *a-b*.

The mechanism above described may be the same as that common to the commercial Underwood machine.

For holding cards, envelops, or other work-pieces, there are employed rolls 46 in front of the platen adjacent the printing point and held against the work-piece by spring-pressure, so that the work is held closely against the platen at the printing point. These rolls 46 may be located on opposite sides of the usual center type-guide 47, the latter being mounted on the type-bar segment 17. The rolls bear upon the visible side of the platen at or adjacent to the printing line, with their axes perpendicular to the platen axis.

These rolls or card-holders may be located between the inner ends of scale-plates or wings 48, the upper edges 49 of which bear against the platen at the base of the printing line on the platen when the latter is in lower-case position and serve as gages to indicate the position of the printing line on the work-sheet, said wings also having the usual scale markings at letter-space intervals along the indicating edges 49. The wings 48 are mounted to swing on rods or pintles 50, each having a screw-threaded portion 51 for connection with a bracket 52 secured by screws 53 to the type-bar segment. The wings are arranged to swing toward and from the platen and are normally held with their edges 49 bearing against the platen or work-piece by means of coil springs 54. The wings may be provided with depending lugs 55, which, by engaging the face of the segment plate 17, will limit the swinging movement of said wings.

The rolls 46 are rotatably mounted on arms 56, which are pivoted on the pintles 50 to enable said rolls to swing toward and from the platen. More specifically, the mounting of each roll-carrying arm 56 is provided by means of a pivot-opening 57 in the lower squared end 58 of the arm 56, said opening 57 receiving a reduced end 59 of the pintle 50, said end 58 fitting in a recess 60 in the bracket 52, whereby movement of said arm or the roll 46 in a direction lengthwise of the platen is prevented. Each roll 46 is held with a yielding pressure against the platen by a leaf-spring 61 connected by 130

a screw 62 to the squared end 58 of the roll-carrying arm, the lower end of the spring normally bearing against a holding block or arm 63 to hold the spring under tension.

5 Each of said blocks 63 is mounted by a pivot screw 64 on the segment 17 to swing from the normal horizontal position, in which it underlies the lower end of the spring 61 and applies tension thereto, to the dotted-line position (Fig. 2), in which the tension is removed. The rolls 46 may then swing freely away from the platen a limited distance, as may be desirable in manifolding or other work in which it is preferred not to use said 15 rolls.

In order that the card-holding rolls 46 may move freely over the work-piece when the carriage moves in letter-feed direction, or in the opposite direction, without producing any drag on the work-piece or tendency to displace it, anti-friction bearings are provided for the rolls. The mounting of each roll on its bearings is also such that the roll may move up and down freely on its 20 supporting spindle 56 with the platen when the latter is shifted between upper and lower-case positions. The position of the roll relative to the work thus remains unchanged during the case-shifting movements,

30 permitting such movements without displacement or disarrangement of the work-piece.

The anti-friction bearings for the rolls comprise upper and lower sets of bearing balls 65 and 66 between the hollow cylindrical sleeve or roll 46 and the spindle or arm 56. The bearing balls are held in a cage or spacer 67, which surrounds the spindle or stem 56, and is permitted a limited up-and-

40 down movement relative to both the roll and its spindle as said roll moves up and down. The parts are shown in Fig. 6 in their normal lower-case position, in which the roll 46 is at its lowest position determined by

45 the inturned flange 68 at the lower end of the roll bearing against the shoulder provided by the squared end 58 of the supporting arm. To limit the downward movement of the cage 67, the arm 56 is provided with a

50 shoulder 69 on which said cage rests. As the platen is shifted from lower-case to upper-case position (Fig. 5), the roll 46 moves upwardly on the stem 56, rolling on the bearing balls, which also roll upwardly on said stem to the Fig. 5 position. A screw 70 threaded into the upper hollow end of the stem 56 limits the upward movement of the cage 67, which, in turn, provides a stop to limit the upward movement of the roll 46.

55 The card-holding rolls 46 comprise the roll portions, which run upon the platen, and the ball-containing barrel portions, these portions being separated by the line 46*, Fig. 6. The barrel portions extend 60 downwardly a considerable distance below

the printing line and are tangent to the platen, and thereby may provide guides for the leading edge of a work-piece as said edge is advanced beyond the front platen feed roll 45, so that the work-piece is guided 70 to the platen at the printing line and gripped between the platen and the upright rolls 46. The work-piece is guided and supported above the printing line by rolls 71, arranged to overlie the side margins of the 75 work-piece and hold it against the platen. Said rolls 71 may be carried by spring fingers 72 pivotally mounted on a tie-rod 73 of the platen frame, said spring fingers being normally held in operative position by 80 spring-pressed detent rolls 74, which engage in a groove in the rod 73. This construction permits said fingers, with the rolls 71, to be swung rearwardly away from the platen, and also permits said rolls to be shifted 85 lengthwise of the platen to adjust them to a work-piece of any width or at any position lengthwise of the platen.

The rolls 46 hold the card or other work-piece firmly against the platen at the printing point, and as they roll on the platen without substantial friction or drag, they have no tendency to displace the work, but, on the contrary, hold it firmly to the platen, and thus prevent any displacement or shifting of the work over the platen surface. The rolls are effective to hold the work not only during the travel of the platen lengthwise, but also during its case-shifting movements.

An important function of the rolls 46 is 100 to hold the card or work-piece securely while being written upon close to its bottom margin, particularly where said writing involves case-shifting movements of the platen, and to hold the work firmly against the platen 105 at the printing point when the bottom edge of the work-piece temporarily overlies a wing 48, as may sometimes occur. Thus, for example, as shown in Fig. 2, the card 75 has been carried upward, so that its bottom edge 110 is very close to the printing line. This view shows the platen in upper-case position and the rolls 46 moved upwardly with the platen and work-piece. If now the platen is dropped to lower-case position, the lower 115 edge of the card 75 may engage over the outer surface of the wings 48, because the edges 49 bear directly on the platen. The rolls 46 being between the inner upright edges 76 of said wings and the printing center, are effective to hold the card firmly 120 against the platen at the printing point, notwithstanding the fact that the card beyond said rolls may be held outwardly a slight distance by the wings. When the platen is 125 moved lengthwise, to carry either side edge of the work-piece toward the printing center, so as to pass beyond the underlying wing 48, said edge will be pressed against the platen by the adjacent roll, and the card 130

will, when the platen is moved in the reverse direction, be guided beneath said wing. When the platen is rotated by the line-spacing mechanism, the work-piece 75, being held against the platen, is carried therewith for line-spacing it in the usual manner, but the position of the rolls 46 remains unchanged. That is to say, during the line-spacing operation, the work-piece is shifted relatively to the rolls 46, so that the rolls are positioned to bear on the work at the new printing line.

Variations may be resorted to within the scope of the invention, and portions of the improvements may be used without others.

Having thus described my invention, I claim:

1. In a typewriting machine, the combination with a platen having a case-shifting movement, of a work-piece-holder comprising an upright, pivoted, cylindrical roll, means to hold the roll with a yielding pressure against the work on the platen adjacent the printing point to roll on the work as the latter moves with the platen in letter-feed direction, a stationary support on which the roll is mounted to shift endwise up and down with the work during the case-shifting movements of the platen without movement of the roll relative to the work, and means for holding said roll with a yielding pressure against the work.

2. In a typewriting machine, the combination with a carriage and a rotary platen shiftable thereon to upper and lower-case positions, of a work-piece-holder comprising an upright, cylindrical roll arranged adjacent the printing point to bear against a work-piece on the platen, and an arm on which said roll is mounted to rotate to permit the roll to run on the work during the travel of the carriage, said roll freely movable endwise on said arm in a direction to permit it to move with the platen and work-piece during the case-shifting movements of the platen, said arm having a stationary mounting.

3. In a typewriting machine, the combination with a rotary platen and a type-bar support relatively shiftable to different case-positions, said platen having a letter-feed travel in the direction of its length, of a work-holding, pivoted, cylindrical roll arranged to bear against a work-piece on the platen and to roll on said work-piece during the travel of the platen in letter-feeding direction, said roll mounted on said support for endwise bodily shifting movement thereon in an up and down direction to permit relative shifting of said roll and support during a case-shifting movement while maintaining a substantially constant relative position of the roll and work-piece during such shifting movement.

4. In a typewriting machine, the combina-

tion with a rotary platen shiftable to upper and lower-case positions, of a stationary support, an arm extending upwardly in front of the platen and pivotally mounted on said support to swing toward and from the platen, a work-holding roll mounted on said arm to bear against a work-piece on the platen, means to press said arm toward the platen to hold said roll with a yielding pressure against the work-piece on the platen, and anti-friction rolling bearings interposed between said arm and roll and arranged to permit the roll to rotate freely on said bearings and also to move freely up and down thereon relatively to said arm, whereby the roll may run on the work-piece during the movement of the platen in letter-feeding direction, and may also move up and down with the platen during a case-shifting movement, the work-piece being held firmly against the platen by the roll during such feeding and shifting of the work without being dragged or displaced by said roll.

5. In a front-strike typewriting machine, the combination with a revolvable platen and types to print at the front face thereof, of pivoted, upright, cylindrical, work-holding rolls in front of the platen and arranged to bear against a work-piece on the platen at the printing line, said rolls extending a substantial distance below the printing line and adjacent to the platen to form guides for the leading edge of a work-piece, arms on which said rolls are supported, a stationary support on which said arms are mounted to swing toward and from the platen, and springs to swing the arms toward the platen and hold said rolls against the work-piece on the platen, the platen being shiftable up and down to upper and lower-case positions, said rolls arranged to move freely endwise up and down on their supporting arms during the case-shifting movement of the platen, whereby the positions of the rolls relative to the work-piece remain substantially unchanged during a case-shifting movement of the platen.

6. In a typewriting machine, the combination with a rotary platen, of a stationary support, scale-plates mounted to swing on said support and having edges to bear against the platen adjacent the printing line at each side of the printing point, and upright work-holding rolls arranged to bear against the platen at the printing line, said rolls interposed between the printing point and the ends of said plates nearest the printing point.

7. In a typewriting machine, the combination with a rotary platen, of wings located on opposite sides of the printing point with their inner ends spaced from said printing point, said wings each having an edge extending along the platen and bearing against the platen at or adjacent to the printing line,

- and work-holding rolls located between the printing point and said inner ends of said wings for holding a work-piece firmly against the platen at the printing point.
8. In a typewriting machine, the combination with a rotary platen, of wings located on opposite sides of the printing point with their inner ends spaced from said printing point, said wings each having an edge extending along the platen and bearing against the platen at or adjacent to the printing line, and work-holding rolls located between the printing point and said inner ends of said wings for holding a work-piece firmly against the platen at the printing point, the platen being shiftable up and down relatively to the said wings to upper and lower case positions, said rolls also shiftable up and down with the platen.
9. In a typewriting machine, the combination with a rotary platen shiftable up and down for printing in different case positions, of a stationary support, wings mounted on said support in front of the platen and extending upwardly therefrom, the upper edges of said wings extending along the printing line on the platen when the latter is in lower-case position, swinging arms mounted on said support and extending upwardly in front of the platen between the inner ends of said wings and the printing point, work-holding rolls rotatable on said arms, and means to hold said rolls with a yielding pressure against the platen at the printing line, said rolls mounted to move up and down on said arms to shift with the platen.
10. In a typewriting machine, the combination with a rotary platen shiftable up and down for printing in different case positions, of a stationary support, wings mounted on said support in front of the platen and extending upwardly therefrom, the upper edges of said wings extending along the printing line on the platen when the latter is in lower-case position, swinging arms mounted on said support and extending upwardly in front of the platen between the inner ends of said wings and the printing point, work-holding rolls rotatable on said arms, and means to hold said rolls with a yielding pressure against the platen at the printing line, said rolls mounted to move up and down on said arms to shift with the platen, said rolls extending downwardly a substantial distance below the printing line and forming means to guide a work-piece to the printing line as it is advanced around the platen.
11. In a typewriting machine, the combination with a rotary platen and a type-bar support, said platen and support relatively shiftable to different case positions, an upright, cylindrical roll providing a work-holding device mounted on said support and arranged to bear against a work-piece on the platen, and anti-friction means rolling between said roll and said support during a case-shifting movement, permitting the roll to move endwise to maintain a fixed position relative to the work-piece during said case-shifting movement.
12. In a typewriting machine, the combination with a rotary platen shiftable to different case positions, of an upright work-holding roll, a support on which it is carried, means to hold the roll with a yielding pressure against a work-piece on the platen, said roll arranged to run on the work-piece during the letter-feed movements of the platen, and anti-friction means between said support and said roll permitting the roll both to rotate and to move endwise freely relatively to said support during a case-shifting movement in such direction that the roll is carried up and down by the platen and its position on the work-piece maintained unchanged during the case-shifting movement.
13. In a typewriting machine, the combination with a rotatable platen, having a case-shifting movement, of a stationary card-holder mounted on the machine and comprising supporting means and rolls rotatable thereon, said rolls positioned to engage a card or work-piece and hold it on the platen with sufficient pressure to prevent slipping of the work-piece on the platen surface during the rotation and letter-feed movements of the platen when said work-piece is held on the platen solely by said rolls, the latter having connection with their supporting means, permitting them to roll freely on the work-piece, during said letter-feed movements of the platen, and permitting the platen to move them freely on their supporting means without rotation, as the platen is shifted, to thereby maintain the relative position of the rolls and work-piece unchanged as the platen shifts.
14. The combination with a platen shiftable to upper and lower case positions, of a card-holder comprising a stationary support and an upright roll thereon positioned to bear against a card or other work-piece on the platen and cause the work-piece to be moved with the platen as the latter is shifted, and anti-friction bearing balls interposed between the roll and its support, and arranged to permit the roll both to rotate and to be moved freely up and down by the platen during the case-shifting of the platen, to maintain the relative position of the roll and work-piece unchanged.
15. The combination with a platen shiftable to upper and lower case positions, of card-holding means comprising arms pivoted on a stationary support to swing toward and from the platen, upright rolls mounted to rotate on said arms and posi-

tioned to bear against a card or other work-piece on the platen, at opposite sides of the printing point, means to hold said rolls with a yielding pressure against the work-piece to roll thereon as the platen is moved in letter-feed direction, and anti-friction means interposed between the rolls and their supporting arms permitting the rolls both to rotate and to be moved bodily up and down by the platen during a case-shifting movement.

16. In a typewriting machine, the combination with a traveling platen shiftable to upper and lower case positions, of a card-holder comprising an upright roll positioned to bear against a card or other work-piece on the platen at the printing line on the platen, a swinging support comprising a spindle on which said roll is mounted for 20 rotation and for movement lengthwise relatively to the spindle, and bearing balls interposed between the roll and the spindle and arranged to run on the roll and spindle during said rotative and lengthwise movement of the roll.

17. In a typewriting machine, the combination with a revolute platen having a letter-feed travel in the direction of its length and shiftable up and down to different case positions, of wings located on opposite sides of the printing center, a stationary support on which said wings are pivoted, springs to swing said wings toward the platen and cause their upper edges to bear 35 against the platen along the printing line, work-holding means arranged to bear against a card or other work-piece on the platen, said means located between the printing center and the inner ends of said wings and arranged to move up and down with the platen and work-piece when the platen is shifted to different case positions, and means whereby the work-holding means is caused to bear against the work-piece with sufficient 45 pressure to hold the work-piece from moving on the platen.

18. In a typewriting machine, the combination with a roller platen shiftable up and down to upper and lower case positions, of 50 wings mounted on a stationary support with their upper edges bearing against the platen along the printing line when the platen is in lower case position, the platen being

shiftable relatively to said wings whereby the printing line is spaced from said wings 55 when the platen is in upper case position, and card-holding devices positioned between the printing point and the inner ends of said wings and arranged to bear against a work-piece on the platen, said devices being shiftable up and down with the platen and work-piece, whereby when the bottom edge of the work-piece is at or close to the printing line and the platen is shifted upwardly and carries said edge beyond said 60 wings and is then returned so that the work-piece overlies said wings, the work-piece is held firmly against the platen at the printing point by said holding devices.

19. In a typewriting machine, the combination with a roller platen and a stationary support, of a work-holder comprising an arm mounted on said support to swing toward and from the platen, a roll mounted on said arm, a leaf spring secured to said arm 75 and depending therefrom, and a tensioning device for said spring mounted on said support to engage behind the spring and cause the latter to hold said roll with a yielding pressure against the platen, said tensioning 80 device shiftable to release the spring and permit the roll to swing freely away from the platen.

20. In a typewriting machine, the combination with a roller platen and a type-bar 85 support, of scale plates, pintles by which said plates are pivotally mounted on said support to permit said plates to swing toward and from the platen, springs to hold said plates against the platen with their 90 upper edges extending along the printing line, work-holding devices, comprising arms mounted to swing on said pintles, rollers carried by said arms, and springs to cause said rollers to bear against the platen at the 95 printing line, the platen being shiftable relatively to said support and plates to upper and lower case positions, said rollers mounted to shift on said arms with the platen and thereby maintain a fixed position relatively 100 to the work-piece during a case-shifting movement of the platen.
